CLAIM

The ornamental design for a drinking fountain, as shown and described.

DESCRIPTION

FIG. 1 is a perspective view of a drinking fountain according to our design.

FIG. 2 is a front view of the drinking fountain.

FIG. 3 is a left side view of the drinking fountain.

FIG. 4 is a right side view of the drinking fountain.

FIG. 5 is a back view of the drinking fountain.

FIG. 6 is a top view of the drinking fountain; and,

FIG. 7 is a bottom-view of the drinking fountain.

The broken lines in the drawings represent portions of the drinking fountain and form no part of the claimed design.

1 Claim, 7 Drawing Sheets
